ERICSSON H. MERRITT, OF LOCKPORT, NEW YORK, ASSIGNOR TO MERRITT ENGINEERING & SALES COMPANY, INC., OF LOCKPORT, NEW YORK, A CORPORATION OF NEW YORK

STEADY REST FOR VENEER LATHES

Application filed September 30, 1927. Serial No. 222,984.

This invention relates to improvements in lathes, and, while it may be employed to advantage in numerous connections, it is particularly adapted for use in connection with lathes in which the material worked upon varies in length, as, for example, in veneer lathes such as those shown in Letters Patent to Louis G. Merritt, No. 699,547, issued May 6, 1902, and in Letters Patent to Ericsson H. Merritt, No. 1,617,409, issued February 15, 1927.

It is a general object of the invention to improve and simplify the operation of such machines as regards the engagement, retention and release of the material being worked upon.

A more specific object of the invention is that of providing means for readily moving the spindle-supporting members of such machines into or out of operative position to engage, steady or release the material, as aforesaid.

Other objects of the invention will in part be obvious and will in part appear hereinafter.

The invention accordingly comprises the features of construction, combination of elements and arrangement of parts which will be exemplified in the construction herein-after set forth, and the scope of the application of which will be indicated in the claims.

For a fuller understanding of the nature and objects of the invention reference should be had to the following detailed description taken in connection with the accompanying drawings, in which:

Figure 1 is a perspective view of one end of a veneer-cutting machine showing the improved construction and the general assembly of the machine;

Fig. 2 is a vertical, longitudinal sectional view of the same;

Fig. 3 is an enlarged detailed sectional view taken between the arrows 3-3 in Fig. 2; and

Fig. 4 is a detail view, partly in section and partly in elevation, taken in the direction of the arrows 4-4 in Fig. 3.

In the exemplification shown in the drawings, the numeral 10 indicates the bed of a lathe, on the upper face of which are posi-

tioned longitudinal slideways 11 and 12. Slidably mounted on said slideways is a steady rest member 13, which is adapted to be released for movement on the slideways and secured in position with respect to the bed of the machine by means of the bolts 14 and the wedge 15 which cooperates with an inclined face of the slideway 12.

Although veneer-cutting machines are usually constructed with power drive mechanisms at both ends, for convenience only one end of a veneer-cutting machine has been shown in the drawings, it being understood that the machine may be of any desired structure at the other end. The drive mechanism shown comprises a driving gear 16, which, when the machine is in cutting operation, rotates a spindle 17, which is held in suitable bearings 18 and 19, by means of a sleeve 20 and a key 21 cooperating with a groove 22 in the spindle 17.

Since the material to be worked on by the machine may vary considerably in length, it is desirable, as shown by the Merritt patents aforesaid, to provide means for moving the spindle inwardly and outwardly longitudinally of the lathe, and in the present embodiment this movement is accomplished by means of the screw-threads 23 on the spindle 17 and a cooperating nut 24, which is turned when desired by means of a wheel 25. In the present embodiment the wheel 25 is shown driven by a motor 26, although other suitable construction may be used, it being understood that when the spindle 17 is being driven by the gear 16 the wheel 25 and its driving means are idled.

Heretofore, in order to steady the chucking end of the spindle, particularly when in extended position, and thus to allow a spindle of smaller diameter to be used, sliding steady rests have been provided which, though similar in construction to the steady rest 13 to the extent that the spindle passed therethrough and the steady rest was slidable along the lathe bed, were, nevertheless, moved longitudinally of the lathe bed by hand. To obviate this difficulty, the present invention provides a connection between the spindle and the steady rest whereby the steady rest may

be moved automatically along the longitudinal axis of the lathe when the spindle is advanced or retracted. By reference to Fig. 3 of the drawings, it will be seen that a particularly simple and efficient means for accomplishing this purpose has been provided, in that the spindle 17 is provided with a channel 27, in which is seated a bearing 28 carried by the steady rest 13. For convenience in assembly, this bearing 28 is split as at 29, and at one end is closed by a plate 30, which is connected to one face of the bearing by bolts 31. Therefore, although the spindle 17 is free to rotate in the bearing 28, nevertheless, endwise movement of the spindle 17 with respect to the bearing 28 and the steady rest 13 is prevented. As a result, when the steady rest 13 is unclamped from the slideways 12 and the spindle 17 is advanced or retracted, the steady rest 13 simultaneously will be moved longitudinally of the lathe bed and may be again clamped fixedly in position by the bolts 14.

The spindle 17 is also provided with a chuck-member 32 adapted to engage the material being worked upon, and in the exemplification shown, the veneer-cutting machine is provided with cutting elements 33 extending longitudinally of the bed of the machine and being adapted to be moved inwardly in the usual manner as the cutting progresses.

Another feature of the present invention is shown particularly in Fig. 4 of the drawings, wherein the face of the steady rest 13 toward which the cutting members 33 approach is cut away as at 34, thus allowing of a substantially complete utilization of the log being turned, since the cutting members may approach quite near to the axis of the lathe 40 without contacting with the steady rest.

Since certain changes may be made in the above construction, and different embodiments of the invention could be made, without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described and all statements of the scope of the invention which as a matter of language might be said to fall therebetween.

Having described my invention, what I claim as new and desire to secure by Letters Patent is:

1. In a veneer lathe, in combination, a lathe bed, slideways positioned longitudinally with respect to said bed, a steady rest slidably positioned on the slideways, a spindle mounted above said bed, means for moving the spindle longitudinally of said bed, a veneer-cutting knife movable axially toward said spindle, and means associated with said spindle for

moving said steady rest along the slideways when the spindle is moved longitudinally thereof in either direction; said steady rest being formed with a cut-away face on the side toward said knife whereby the latter may be moved closely adjacent to said spindle. 70

2. In a lathe, in combination, a lathe bed, a spindle mounted above said bed and axially adjustable for chucking and rotatable for driving, a steady rest movably positioned on the lathe bed, a connection between said spindle and said steady rest whereby the steady rest is moved by the spindle longitudinally of the axis of the lathe as the spindle is adjusted axially, a split bearing in the steady rest which coacts with the channel in the spindle to prevent relative longitudinal movement between the spindle and the steady rest, and a veneer-cutting knife movable axially toward said spindle; said steady rest having a flattened face on the side toward said knife whereby the latter may be moved closely adjacent to said spindle. 75 80 85

In testimony whereof I affix my signature.
